UNITED STATES PATENT OFFICE.

HARLOW D. GAINES, OF NEW YORK, N. Y.

DESIGN FOR AN ADVERTISING FLY-NET.

SPECIFICATION forming part of Design No. 26,693, dated February 23, 1897.

Application filed December 22, 1896. Serial No. 616,664. Term of patent 7 years.

To all whom it may concern:

Be it known that I, HARLOW D. GAINES, a citizen of the United States, residing at New York, in the county of New York and State of New York, have invented and produced a new and original Design for an Advertising Fly-Net for Horses, of which the following is a specification, reference being had to the accompanying drawings, forming part hereof, and in which—

Figure 1 is a view of one face or side of an advertising fly-net for horses, mules, and the like, showing my design; and Fig. 2 is a view of the other side or face of the same. These two views are deemed necessary to fully illustrate my design.

The leading feature of my design consists in a side-by-side arrangement or display of one or more discontinuous reticulated or open-work bars and one or more solid or sheet-like fields which do not extend the one under the other, whereby identity of appearance on each face of the article is presented.

a are the reticular or open-work stripes or bars, and b are the solid web or sheet-like stripes, bars, or fields, visible when viewed from either side or face of the fly-net, and one or both of which may be emblazoned with any desired advertisement. When viewed from either side or face of the fly-net, the field b and bar a adjoin and are not superposed, and the appearance thus imparted may not be caused to disappear without physical destruction of that which embodies the design. 35

What I claim is—

The design for an advertising fly-net, substantially as shown and described.

In testimony whereof I have hereunto signed my name.

HARLOW D. GAINES.
